UNITED STATES PATENT OFFICE

RALPH H. CHILTON, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed November 18, 1926. Serial No. 149,106.

This invention relates to cooling units for mechanical refrigerators, and more particularly to cooling units which are adapted to be installed in refrigerating cabinets of the household type. However, it is to be understood that the present invention may be adapted for larger refrigerating cabinets of the commercial type.

The present invention includes among its objects the provision of a cooling unit of simple and economical construction which will quickly congeal or freeze substances which are placed within a freezing compartment provided by the unit, and which will effectively cool the food compartment of the cabinet.

Further objects and advantages of the present invention will be apparent from the following description, reference being had to the accompanying drawings, wherein a preferred form of the present invention is clearly shown.

In the drawings:

Fig. 1 is a front view of a refrigerator cabinet with the doors open in order to show the food compartment and a cooling unit within a cooling compartment;

Fig. 2 is a view on a larger scale than Fig. 1, showing the front view of the cooling unit which is suspended within the cooling compartment of a cabinet, the walls of which are shown in vertical section; and

Fig. 3 is a side elevation of the cooling unit drawn to the same scale as Fig. 2.

Referring to the drawings, 20 designates a refrigerator cabinet which provides an L-shaped food compartment 21 separated from a cooling compartment 22 by a horizontal partition 23 and a vertical partition 24. The partition 24 is provided with a flue 25, admitting relatively warm air from the food compartment 21 to the cooling compartment 22; and the partition 23 is provided with a flue 26, admitting cooled air from the compartment 22 to the compartment 21. The partition 23 supports a baffle 27 which prevents moisture, dripping from the cooling unit above, from entering the flue 26. The baffle 27 directs such moisture upon the upper surface of the

partition 23, and this moisture is conducted away through a drain pipe 28.

The cooling unit located within the cooling compartment 22, includes a boiler or header 30 attached to the top wall of the cabinet by bracket members 31 and 32. Condensed refrigerant is conducted to the header 30 from a compressor and condenser (not shown) through a pipe 33 and a fitting 34. Refrigerant is admitted from the fitting 34, as needed, by a float controlled valve (not shown), of suitable construction, located within the header 30. Expanded refrigerant is conducted back to the compressor through a fitting 35 and a pipe 36. The refrigerating compressor and condenser with which the pipes 33 and 36 are connected, may be located outside the cabinet, if desired, or may be placed within a machine compartment located below the food compartment 21, said compartment having a removable front wall 37 provided with louvres 38.

A plurality of looped conduits 40 of metal of good thermal conductivity are connected with the header 30 and are arranged in horizontal rows, one on each side of a freezing space 41 which is enclosed by the header 30 and the straight, vertical branches 42 of said loops. The branches of the loops which are more remote from the space 41 are helical in formation so as to provide a relatively large area of heat absorbing surface within the space limited by the walls of the cooling chamber 22.

By virtue of this arrangement, the cooling unit provides what may be termed a freezing zone for quickly freezing or congealing a substance and provides what may be termed a cooling zone for the general refrigeration of the refrigerator. The freezing zone, formed by the ducts 42, is nested within the cooling zone, formed by the ducts 43, and said freezing zone is thus protected from warming action of the circulating air flowing over the cooling unit.

The freezing space 41 is adapted to receive one or more metal shelves or sleeves 43 which are attached to and thermally connected with the ducts 42. The sleeves receive metal trays 44 containing matter to be frozen.

The freezing space 41 is further isolated from air currents by metal shields 45 which are attached to and thermally connected with the ducts 42. These plates also render the 5 ducts 42 more effective in cooling the air circulating adjacent the outer sides of the plates. Consequently the plates 45 limit the accumulation of frost around the ducts 42 and thus prevent rapid accumulation of frost 10 on the coils 43 such as would impede circulation of air through them.

The present invention is particularly adapted for use in a cabinet in which the number of heat units to be given up by the circulating air is relatively great, such as in a 15 cabinet having a relatively large food space, or in one which is located in a warm place.

It is quite apparent that the ducts 43, being 20 tortuous, provide a larger heat transfer surface than the ducts 42 throughout the same height of said ducts. Consequently more gas and less liquid will be present in ducts 43 than in ducts 42. This difference of apparent 25 density of refrigerant in the ducts 43 and 42 provides unbalanced columns of refrigerant causing what may be termed a prevalent flow of refrigerant from the header 30, downwardly through the ducts 42, and upwardly through the ducts 43. By establishing a 30 prevalent flow, as above described, in contradistinction to a circuit in which the liquid flows in one direction and vapor in the opposite direction, the upward flow of vaporized refrigerant in one of the opposed branches 35 in which the vaporization is greater, the gaseous refrigerant can escape more readily because its upward movement is not impeded by the movement of the downwardly flowing liquid refrigerant. Thus by my arrangement, I provide a circuit in which the vaporized refrigerant readily flows therefrom and is immediately replaced by liquid refrigerant 40 to thus improve the thermal efficiency of the circuit.

45 The construction and arrangement of the looped conduits are such as to facilitate manufacture. Preferably, the loops are connected with the header before attaching the sleeves. The loops may be bent transversely 50 of the header so that the ducts 42 may be adjusted to fit the sleeves properly in order that a good thermal connection between the sleeves and the ducts 42 may be made.

55 While the form of embodiment of the present invention as herein disclosed, constitutes a preferred form, it is to be understood that other forms might be adopted, all coming within the scope of the claims which follow.

What is claimed is as follows:

60 1. A cooling unit for a refrigerator comprising an elongated header having looped conduits depending from opposite sides thereof, each including a substantially straight branch and a branch having a coiled portion, 65 the similar branches of the conduits on the

respective sides of the header being aligned, the straight branches of all of the conduits cooperating with the header to provide a freezing space.

2. A cooling unit for mechanical refrigerators adapted to be placed in the path of medium to be cooled thereby, said cooling unit including ducts, said ducts having a portion arranged to provide a freezing zone, and another portion arranged to provide a cooling zone, the material of the second-mentioned portion being tortuous and lying spaced from the freezing zone in the path of the circulating medium and so constructed and arranged as to provide a shield of heat-exchange material for shielding the freezing zone from the action of the circulating medium.

3. A cooling unit for mechanical refrigerators adapted to be placed in the path of medium to be cooled thereby, said cooling unit including duct loops having a portion arranged to provide a freezing zone, and another portion arranged to provide a cooling zone, the material of the second-mentioned portion being tortuous and lying spaced from the freezing zone in the path of the circulating medium and so constructed and arranged as to provide a shield of heat-exchange material for shielding the freezing zone from the action of the circulating medium.

4. A cooling unit for mechanical refrigerators adapted to be placed in the path of medium to be cooled thereby, said cooling unit including opposed duct loops, portions of said opposed ducts cooperating to provide a freezing zone therebetween, and another portion being arranged to provide a cooling zone, the material of the second-mentioned portion being tortuous and lying spaced from the freezing zone in the path of the circulating medium and so constructed and arranged as to provide a shield of heat-exchange material for shielding the freezing zone from the action of the circulating medium.

5. A cooling unit for mechanical refrigerators adapted to be placed in the path of medium to be cooled thereby, said cooling unit including opposed duct loops, each of said loops having a portion cooperating with the like portions of the other ducts to provide a freezing zone and each having another portion arranged to provide a cooling zone, the material of the second-mentioned portion being tortuous and lying spaced from the freezing zone in the path of the circulating medium and so constructed and arranged as to provide a shield of heat-exchange material for shielding the freezing zone from the action of the circulating medium.

6. A cooling unit for mechanical refrigerators adapted to be placed in the path of

circulating medium to be cooled thereby, said cooling unit including an upper header and opposed duct loops connected with the header and in parallel circuit relation, portions of said opposed loops cooperating to provide a freezing zone therebetween, and another portion being arranged to provide a cooling zone, said latter portions lying outwardly of the freezing zone in the path of the circulating medium, and shield means interposed between the first and second portions and cooperating with the header for shielding the freezing zone from the action of the circulating medium.

7. A cooling unit for mechanical refrigerators adapted to be placed in the path of circulating medium to be cooled thereby, said cooling unit including an upper header and duct means connected with the header, duct loop means connected with the header and opposed to said duct means, said loop means having a portion cooperating with the duct means to provide a freezing zone therebetween, said loop means having a second portion providing a cooling zone, said latter portion lying outwardly of the freezing zone in the path of the circulating medium, and shield means interposed between the first and second portion and cooperating with the header for shielding the freezing zone from the action of the circulating medium.

8. A cooling unit for mechanical refrigerators adapted to be placed in the path of medium to be cooled thereby, said cooling unit comprising a header, duct means, and duct loop means connected with the header, said loop means having a downwardly extending duct portion cooperating with the duct means to provide a freezing zone and a second portion providing an upwardly extending duct spaced from the first mentioned portion, the material forming the second mentioned duct being tortuous throughout a large portion of its height and providing a relatively larger heat transfer surface than that of the first duct throughout the same height.

9. A cooling unit for a refrigerator comprising a header having looped conduits depending from opposite sides thereof, the adjacent branches of the respective, looped conduits being substantially straight and the other tortuous, the adjacent, straight branches of the conduits cooperating with the header to provide a freezing space, and a plate, thermally connecting the straight branches of the conduit.

10. A cooling unit for a refrigerator comprising a header having looped conduits depending from opposite sides thereof, the adjacent branches of the respective, looped conduits being substantially straight and the other tortuous, the adjacent, straight branches of the conduits cooperating with the header to provide a freezing space, and

a plate thermally connecting the straight branches of the conduit, said plate being secured to said branches on the sides thereof more remote from the freezing chamber.

In testimony whereof I hereto affix my signature.

RALPH H. CHILTON.
